Attys.

UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

CURTAIN-HANGING DEVICE.

1,315,707.

Specification of Letters Patent. Patented Sept. 9, 1919.

Application filed February 10, 1919. Serial No. 276,037.

To all whom it may concern:

Be it known that GUSTAF A. CARLSON, a citizen of Sweden, residing at Chicago, in the county of Cook and State of Illinois, 5 has invented a new and useful Improvement in Curtain-Hanging Devices, of which the following is a specification.

This invention relates particularly to curtain-hanging devices adapted for use in hanging lace curtains or draperies; and the primary object is to provide an improved device which is especially well adapted to the purpose of hanging two pairs of curtains, or the regular curtain and an over-drape.

The invention is illustrated in its preferred embodiment in the accompanying drawings, in which—

Figure 1 represents a broken plan view, 20 illustrating the manner in which the curtain-hanging device is mounted on a window-frame or sash; Fig. 2, a broken elevational view of the same; Fig. 3, a fragmentary view of the curtain rod and the gripper element employed in connection therewith; Fig. 4, a sectional view of the parts illustrated in Fig. 3; Fig. 5, a perspective view of one of the improved brackets employed; and Fig. 6, a broken perspective view, 30 illustrating a slight modification of the improved bracket.

In the construction illustrated, A represents a window-frame or sash; B, B, a pair of brackets applied thereto; and C, C¹, a 35 pair of curtain-rod carried by said brackets. Each of the brackets B comprises a base portion 1 provided with perforations 2, adapted to receive screws 2^a; a relatively long arm 3 which extends outwardly from 40 the outer edge of the base portion and which is curved and provided at its outer end with a loop 3^a, formed by recurring the end portion of the arm back and under the body portion, the extremity being indicated at 3^b; 45 and a relatively short arm 4 which extends outwardly from the other side of the base portion 1 and underlies the loop portion 3^a of the longer arm, from which it is separated by a space 5.

50 The front wall of the loop 3^a is provided with an enlarged opening 6, which communicates with a reduced opening or perforation 6^a in the end or web of the loop, thus forming what is, in effect, a T-slot for the 55 reception of the gripper-member or head of the curtain-rod.

The curtain-rods may be of any approved construction. In the illustration, the curtain-rods are shown as flexible members comprising close-coiled piano steel wire, 60 equipped at the end portions with grippers 7. Each gripper 7 comprises a ring formed of sheet-metal and provided with gripping-jaws 7^a adapted to engage the convolutions of the coil. The member 7 affords a head 65 for the curtain-rod, and the gripping-jaws present beveled or diverging surfaces 7^b which are adapted to be engaged by the walls of the perforations 6^a, it being understood that the loop portion of the member 7 70 can pass through the enlarged opening 6 in the front wall of the loop but cannot be drawn wholly through the perforations 6^a in the end of the loop. When the curtain-rod is inserted, the coil-spring being placed 75 under tension during this action, the gripping-member will be drawn partially through the perforations 6^a, whose walls engage the diverging surfaces 7^b and cause the gripper to securely engage the curtain-rod. 80

The arm 4 is provided near its outer end with a perforation 4^a with which communicates a comparatively narrow slot 4^b which opens at the end of the arm. It will be understood, therefore, that the gripper 7, 85 constituting the head portion of the rod C¹, may be entered through the slot 4^b, and the gripper will then be drawn partially through the perforation 4^a, so that the curtain-rod will be securely held.

90 The members B are symmetrically formed and are reversible, so that it is unnecessary to make "rights" and "lefts." When the members of a pair of brackets are applied to the frame, they are so turned that the 95 short arms 4 are nearest the opening in the sash, while the arms 3 are remote from each other, the outer ends of the arms being curved toward each other, as will be clearly understood from Fig. 1. When the brackets 100 are applied, the outer end portions of the arms 3, that is, the loop portions 3^a, overlie and practically conceal the arms 4. Thus the brackets present a very neat appearance, as will be understood from Fig. 2. The 105 bracket can be formed conveniently from sheet-metal, the supporting members for each pair of rods being thus formed integrally with each other and with a single attaching base. Thus, the device can be 110 very cheaply manufactured. In the forming process, the arms can be made concavo-

convex in cross-section, thus stiffening them and enhancing their appearance, as in the illustration given.

In the modification shown in Fig. 6, B¹ represents a bracket of the same construction as that shown in Fig. 5 except that the short arm 4^c, instead of having the perforation communicating with a slot which opens at the end of the arm, is provided with a 10 perforation 4^d which communicates with a slot 4^e which opens at the upper lateral edge of the arm 4^c. The other parts of the bracket are designated by the same characters as are used in connection with 15 the bracket shown in Fig. 5. In the case of the modification, the inner curtain-rod has its head entered from above and through the slot 4^e into the perforation 4^d. This is a feasible construction, but the use 20 of the modification would probably make it desirable to provide "rights" and "lefts," inasmuch as it would be desirable to have the slot 4^e open upwardly rather than downwardly.

25 The improved bracket is simple, cheap, strong and durable. When formed from sheet-metal of proper configuration, as illustrated, and nickel-plated, the bracket presents an exceedingly neat and attractive appearance. The brackets are adapted to support the curtain-rods C, C¹ in parallel relation, the arm 4 being preferably about one-half the length of the arm 3, so that the curtain-rods will be spaced apart about 35 the same distance that the inner rod is spaced from the sash or frame.

The foregoing detailed description has been given for clearness of understanding only, and no unnecessary limitation should 40 be understood therefrom, but the appended claims should be construed as broadly as permissible in view of the prior art.

What I regard as new, and desire to secure by Letters Patent, is—

45 1. In means of the character set forth, the combination of a pair of brackets, each comprising a member having a perforate attaching base and arms extending outwardly from directly opposite edge portions of said base, whereby the arms will lie in the same horizontal plane when the bracket is applied, one of said arms being longer than the other and said arms being provided at their end portions with curtain-rod 50 engaging means, and a pair of curtain-rods mounted in parallel relation on said arms.

55 2. A curtain-rod bracket comprising a sheet-metal member formed to afford a perforate attaching base, and integral long and short arms, the short arm extending outwardly from one edge portion of the base and having its outer end provided with a

socket and the long arm being curved to cover the base and the short arm and having a loop-end provided with a socket which is 65 spaced some distance from said first-named socket.

3. In means of the character set forth, the combination of a pair of brackets, each comprising a perforate attaching base, a 70 short arm extending outwardly from the inner edge portion of said base and provided with a socket, a curved long arm extending outwardly from the opposite edge portion of said base and having its end 75 portion provided with a socket lying in substantially the same plane perpendicular to the frame as the socket of said short arm, and a pair of curtain-rods having end portions engaging said sockets.

80 4. A bracket adapted for use in supporting a pair of curtain-rods, said bracket comprising an attaching base provided with perforations, a short arm extending outwardly from one edge portion of said base, and a long arm extending outwardly from the opposite edge portion of said base and curved over the base and having its end portion spaced at a distance from the end 85 portion of the short arm, the end portions of said arms being provided with T-slots 90 affording sockets for curtain-rods.

5. A bracket adapted for use in supporting a pair of curtain-rods, said bracket comprising an attaching base portion with perforations, a short arm extending outwardly from one edge portion of said base, and a directly opposite long arm extending outwardly from the opposite edge portion of said base and having its end portion spaced 95 at a distance from the end portion of the short arm, the outer end portions of said arms presenting walls having perforations therein through which the head portions of curtain-rods may extend, said walls having 100 slots opening into said perforations, whereby the heads of tension-rods may be entered and held in the sockets afforded by said perforations, said arms lying in the same horizontal plane when the bracket 105 is applied.

6. A bracket for the purpose set forth, comprising a sheet-metal member formed to provide a base-portion which has perforations therein, a short arm extending outwardly from one edge of said base-portion, and a long arm extending outwardly from the opposite edge of said base portion and curved to overlie the base-portion, said arms being concavo-convex in cross- 115 section, and having their outer end portions provided with sockets for curtain-rods.

GUSTAF A. CARLSON.
